Primary Examiner — Ian Simmons*Assistant Examiner* — Shannon Morgan(74) *Attorney, Agent, or Firm* — Kagan Binder, PLLC(57) **CLAIM**

The ornamental design for a label for a bottle, as shown and described.

DESCRIPTION

FIG. 1 is a front elevational view of a label for a bottle showing my new design;

FIG. 2 is a top plan view, the bottom plan view being identical thereof;

FIG. 3 is a left side elevational view, the right side view being identical thereof; and,

FIG. 4 is a perspective view of the label for a bottle shown in an alternate configuration.

The portion of FIG. 4 shown in a light coarse dot pattern and outlined in dashed lines of the label for a bottle is for the purpose of illustrating environment, and forms no part of the claimed design.
